UNITED STATES PATENT OFFICE.

BUDD D. GRAY, OF NEW YORK, N. Y.

CARBURETER.

No. 855,170.

Specification of Letters Patent.

Patented May 28, 1907.

Application filed July 14, 1905. Serial No. 269,626.

To all whom it may concern:

Be it known that I, BUDD D. GRAY, a citizen of the United States, and a resident of the borough of Manhattan, and city, county, and State of New York, have invented certain new and useful Improvements in Carbureters, of which the following is a specification.

The invention relates to carbureters, and more particularly to that class thereof designed for employment in connection with explosion engines, and is primarily designed to secure the proper admixture of the air and vapor at all speeds of the motor, and secondarily, at low speeds to prevent the formation of unnecessarily fat mixtures, which is a common fault in the engines now employed.

Referring to the drawing, Figure 1 is a vertical section of a carbureter, showing the application of the invention thereto. Fig. 2 is a detail section taken substantially through the middle of the vaporizing nozzle shown in Fig. 1. Fig. 3 is a view similar to Fig. 1 but illustrating a modification.

Referring to Figs. 1 and 2, the gasoline or other material to be vaporized passes through the supply pipe A into the float chamber B and receptacle E, from which it is drawn through the nozzle D by the air passing through the mixing chamber C in the manner well understood. The mixture then flows through the port H to the motor, the port H being throttled by the valve F connected to the rod G, which is adjusted either manually or automatically as may be desired. Located above the mixing chamber or tube C is the piston valve N connected to the stem M and normally held in its uppermost or inoperative position by the spiral spring O which surrounds the stem M and rests upon the tube C. As the speed of the motor increases the greater suction produced thereby creates a partial vacuum beneath the valve N, which is operated by atmospheric pressure to overcome the spring O, sufficient space being left around the stem M to permit the entrance of the air for the purpose named. As the valve N is thus depressed, its ports PP are brought into correspondence with the ports QQ in the surrounding cylinder, and an additional air supply is thus afforded when the motor is running at high speed.

All of the parts thus far described are in

common use in explosion engines, and the particular forms thereof constitute no part of the present invention, which may be applied in many different ways.

In motors of the class referred to there exists the necessity for governing the supply of gasoline or other vapor so that it will vary with the speed, and particularly to prevent the formation of too rich a mixture at low speeds. In the present instance, this is accomplished by an automatically controlled air director, which at low speeds holds the air current at some little distance from the vapor inlet, and as the speed increases permits the current to come into closer relation with the vaporizing nozzle, and finally at very high speeds the controlling device is removed entirely beyond the nozzle. In this manner it will be seen that the richness of the mixture depends entirely upon the speed of the motor, as at low speeds the vapor entrained by the air current will be of comparatively small amount due to the distance of the current from the nozzle, and as the speed increases more and more vapor will be taken up by the current as it approaches the inlet, and finally at high speeds the controller will be moved entirely away from the nozzle permitting the air current to extract the maximum amount of vapor therefrom. It is to be noted that the critical point in actual practice is passed at slow and moderate speeds and that at high speeds the exact amount of entrained vapor becomes relatively unimportant and hence no governing device is essential therefor.

The air current director as herein illustrated is in the form of a cylinder J surrounding the nozzle D and passing through the mixing chamber C. On the outer side the cylinder J is formed with a port or opening K and at the opposite side with a port or opening L. It is to be noted that the opening K extends to a considerably lower point in the cylinder J than the opening L, thus causing the air current which passes through the openings K and L to assume an upwardly sloping or oblique direction at low and ordinary speeds. The upper part of the cylinder J is connected to the stem M of the auxiliary air valve N, so that it will move therewith. As previously described, when the motor is running slowly the valve N will be in its up-

permost or inoperative position, thus raising the openings K and L of the cylinder J to a point above the nozzle D and thereby reducing the richness of the mixture. As the speed increases, the suction of the motor depresses the valve N, thus admitting the additional air supply through the ports PP and QQ and at the same time bringing the openings K and L of the cylinder J nearer to the nozzle D and thereby increasing the amount of vapor drawn therefrom. At very high speeds the valve N is still further depressed and the cylinder J therewith until the openings K and L are brought below the top of the nozzle D, at which time as explained the relative amount of vapor entrained by the air current becomes a matter of small importance. It will be seen that in this manner the richness of the explosive mixture depends directly upon the amount of the secondary air supply and indirectly upon the speed of the engine, and without varying the primary air supply.

In Fig. 3 is illustrated a modification involving substantially the same principles. A needle valve T is arranged within the nozzle D-1 and connected to the stem M-1 of the auxiliary air valve N-1. The valve T is provided with the customary longitudinal grooves to permit the medium amount of vapor to be withdrawn from the nozzle D-1 when the motor is running slowly and the valve N-1 and needle valve T are in their uppermost positions. As the speed of the engine increases, atmospheric pressure causes the inward movement of the valve N-1 against the force of spring O-1 until the ports P-1, P-1 and Q-1, Q-1 coincide and admit the auxiliary supply of air therethrough. Simultaneously the needle valve T is depressed thereby permitting an additional amount of vapor to be withdrawn from the nozzle D-1 by the current of air in the mixing chamber C-1. As in the previously mentioned case the supply of vapor will be proportional to the auxiliary air supply and hence to the speed of the engine.

Having thus described the invention, its construction and mode of operation, what is claimed and desired to be secured by Letters Patent of the United States is as follows:

1. In a carbureter having an air admission opening of unchanging constant area, the combination with said opening of fuel-admitting means with which the air entering said opening co-operates, and mechanism controlled by the suction of the motor, and adapted on the increased speed of the motor, to increase the fuel entraining power of the air.

2. In a carbureter, the combination with auxiliary air-admitting means, of fuel-controlling means connected thereto and oper-

ated thereby; whereby the fuel supply will vary in direct proportion to the supply of auxiliary air.

3. In a carbureter, the combination with a fuel-admitting nozzle, of an air stream director co-operating with the nozzle, and means controlled by the suction of the motor for adjusting said director relatively to the nozzle.

4. In a carbureter, the combination of air-admitting means, fuel-admitting means, an air stream director co-operating with the fuel-admitting means to vary the amount of fuel entrained, and connections between the director and air-admitting means for controlling the entraining power of the air stream.

5. In a carbureter, the combination of an auxiliary air-admitting means, fuel-admitting means, an air stream director co-operating with the fuel-admitting means to vary the amount of fuel entrained, and operative connections between the director and auxiliary air-admitting means, acting to control the entraining power of the air stream.

6. In a carbureter, the combination of a fuel-admitting nozzle, a movable cylinder provided with an air stream director co-operating with the nozzle to vary the amount of fuel entrained, and means controlled by the suction of the motor for moving the cylinder, and thereby varying the fuel entraining power of the air stream.

7. In a carbureter, the combination of a fuel-admitting nozzle, an adjustable cylinder provided with an air stream director co-operating with the nozzle to vary the amount of fuel entrained, said director being formed to cause the air current to flow in an oblique direction, and means controlled by the suction of the motor for moving the cylinder, and thereby varying the entraining power of the air stream.

8. In a carbureter, the combination of a fuel-admitting nozzle, an adjustable cylinder provided with an air stream director co-operating with the nozzle and movable out of operative relation to the same, and automatic means controlled by the speed of the motor for so adjusting the cylinder that at high speeds the air stream director will be moved to an inoperative position.

9. In a carbureter, the combination of a fuel-admitting nozzle, an air stream director co-operating therewith and movable out of operative relation thereto, and means controlled by the speed of the motor for adjusting the air stream director relatively to the nozzle at low speeds, and acting to move the air stream director out of operative relation to the nozzle at high speeds.

10. In a carbureter, the combination of a fuel-admitting nozzle, primary air-admitting means adapted to supply air in constant volume, auxiliary air-admitting means controlled by the speed of the motor and adapt-

ed on increased speed to admit an auxiliary supply of air in increasing volume, and a device controlled by the auxiliary air-admitting means, and acting to vary the entraining power of the primary air on the nozzle in direct proportion to the auxiliary air supply.

5 In testimony whereof I have subscribed

my name to this specification in the presence of two attesting witnesses.
